UNITED STATES PATENT OFFICE.

FRANK A. WELLS, OF NEW YORK, N. Y.

DESIGN FOR A SITZ-BATH TUB.

SPECIFICATION forming part of Design No. 34,145, dated February 26, 1901.

Application filed January 30, 1901. Serial No. 45,392. Term of patent 7 years.

To all whom it may concern:

Be it known that I, FRANK A. WELLS, a citizen of the United States, residing in New York city, borough of Manhattan, State of New York, have invented and produced a new and original Design for Sitz-Bath Tubs, of which the following is a specification, reference being had to the accompanying drawings, forming part hereof, wherein—

10 Figure 1 is a front elevation of a sitz-bath tub embodying my design, and Fig. 2 is a vertical cross-section thereof.

The essential feature of my design consists in a sitz-bath tub having a flaring rim at its 15 open top, the outer surface of the body portion being curved inwardly and convexly in a vertical direction, and above the body portion rises a back provided with sides, the front edges of which sides are curved or 20 rolled, and beneath the bowl are pedestals extending parallel to the sides from front to rear and the walls of which pedestals in a vertical direction curve inwardly and convexly downwardly.

25 In the drawings the letter A indicates generally the sitz-bath tub, at the open top of which the flaring rim is indicated at *a*, below

which is an inwardly-curved surface *b*, and below the latter the surface *c* is curved convexly, and this surface is extended under to 30 the bottom portion *d*. At the rear portion of the body the back *B* extends in an upward direction, the front edges of the sides *B'* of which back are curved or rounded at *e* and extend upwardly and rearwardly to the 35 top edge *f*, and beneath the edge *f* the outer wall of the back *B* is curved inwardly at *g* and merges into the convex curve *c* of the bowl portion. The pedestals are indicated by the letter *C*, and they extend from front 40 to rear at opposite sides beneath the body, and their surfaces are embellished by opposed inward curves *h*, beneath which are opposed convex curves *i*, said curves leading downwardly, and they extend around the pedestals 45 symmetrically.

What I claim is—

The design for a sitz-bath tub, substantially as shown and described.

FRANK A. WELLS.
